OIL PUMP

Application filed July 16, 1929, Serial No. 378,636, and in the Union of Soviet Socialist Republics
May 24, 1929.

My invention relates to oil well pumps and has a particular reference to pumps adapted to pump oil, water, brine etc. from deep wells. Due to the limitation of the suction height, 5 the pumping mechanism in deep wells must be placed at the bottom of the well, bringing operating connections to the outside. Ordinary deep well pumps are provided with rigid rods extending from the mouth of the well 10 where an operating engine or motor is located, to the bottom where the pump is placed. This arrangement causes considerable difficulties when the depth of the well reaches a few thousand feet, due to the great weight of 15 the rod, its interference with the exhaust pipe from the pump, and the large amount of friction caused partly by the elastic distortion of the rod, partly by the unavoidable curvature of the well itself. 20 In order to obviate these difficulties I provide an auxiliary reciprocating device adapted to be operated by the pressure of a liquid. This device is operatively connected with the pump and is also placed at the bottom of the 25 well. A pipe extends from this device to the top of the well where another similar device is located for imparting a reciprocating movement to the liquid column in the pipe and thereby causing a reciprocating movement of 30 the auxiliary device and of the pump.

With this arrangement there are no rods or cables passing through the well, so that a great saving in power is effected, with a very efficient control of the operation of the pump. 35

My invention is explained more fully in the accompanying specification and drawing in which—

Fig. 1 is a sectional elevation of the well with its casing pipe and the pump, Fig. 2 is 40 a sectional elevation of the upper operating device, and Fig. 3 is an outside view of the apparatus showing well in section.

My pump consists of a cylinder 1 adapted to be fitted at the bottom of a casing pipe 2. 45 It has a flattened bottom portion with holes 3.

The holes may be covered with screens in order to prevent any sand or dirt from passing through the pump.

The cylinder 1 has a wall 4 in the middle 50 with a ball valve 5 which admits liquid from

the well into the casing pipe above the valve. A piston 6 is slidably fitted in the cylinder 1 and is provided with a ball valve 7 adapted to admit the liquid into the space above the piston. A rod 8 extends from the piston and 55 passes through an antifriction bushing 9 fitted in the lower end of a second or auxiliary cylinder 10 the outside diameter of which is smaller than the inside diameter of the casing pipe 2, so that liquid can pass in the clearance 60 around this cylinder. A second or auxiliary piston 11 is slidably fitted in the cylinder 10 and is attached to the upper end of the rod 8. A pipe 12 is fitted in the piston or plunger 11. The upper end of this pipe slides in the 65 lower end of an auxiliary or service pipe 13 which is fastened in the upper end of the cylinder 10. Apertures 14 are provided in the walls of this cylinder for admitting liquid from the casing pipe into the cylinder. These 70 apertures may be covered with screens to prevent any dirt from passing inside.

The upper end of the casing pipe 2 has a plug 15 with a valve 16. The ball of the valve is pressed against its seat by a lever 17 75 with a weight 18 which can be adjusted in order to maintain a desired pressure in the casing pipe.

The upper end of the service pipe 13 extends into one end of a cylinder 19, which with a piston 20 represents an auxiliary or service pump. The other end of this cylinder is connected by a pipe 21 with the casing pipe 2 below the valve 16. The piston rod 22 is operatively connected with an engine or motor 23 80 which imparts to the piston 20 a reciprocating motion. A safety valve 24 is provided and a small intake valve 25 which admits auxiliary liquid into the cylinder 19. This auxiliary liquid fills the space in the pipes 12 85 and 13 and the space in the cylinder 10 below the plunger 11. This auxiliary liquid may be the same which is pumped from the well, or it may be different, water, oil etc. 90

The operation of my pump is as follows.

When the piston 20 is moved to the left it moves the liquid column in the pipes 13 and 12, filling the space under the plunger 11 thereby raising same in the auxiliary cylinder 100

10. The liquid from this cylinder flows into the casing pipe 2 through the apertures 14.

The piston 11 raises also the piston 6 which raises the column of liquid in the pipe 2, filling also the space in cylinder 19 back of the piston 20 through the pipe 21. When a certain limiting pressure is reached, the check valve 16 is forced open against the pressure of the weight 18 admitting the liquid to the 10 upper portion of the pipe 2 for delivering into storage or shipping tanks.

With the return movement of the piston 20 the liquid column in the pipes 13 and 12 is drawn upward causing the piston 11 to drop 15 down under pressure of the liquid in the pipes 10 and 2. The pipe 12 slides down in the pipe 13, and the rod 8 pushes the piston 6 down. The valve 5 becomes closed by the pressure of the liquid, and the piston valve 7 20 opens, admitting the liquid in the space above the piston, into the casing pipe 2. The pressure in the pipes 13 and 12 does not decrease as the amount of liquid forced from the one side of the cylinder 19 equals the amount admitted into the other. For this purpose the 25 volume displaced by the piston 20 is made equal the volume displaced by the piston 11.

Important advantages of my pump are that it does not require any mechanical moving 30 parts in the casing pipe thereby greatly reducing the power requirement by eliminating friction losses; that the pump is directly connected with the source of motive power; absence of any slide valves in the well (such slide 35 valves are difficult to control at the bottom of the well at the great pressures encountered there); simplicity and low cost of construction; large piston travel or stroke possible in the well; absence of by-pass pipes reducing 40 the active diameter of the pump, which may cause difficulties in placing the pump in the well or removing it; possibility to regulate the speed of the pump in accordance with the amount of liquid to be pumped, and this is 45 easily accomplished by varying the power of the motor. Such regulation renders the operation of the pump more effective from geological point of view, and all the troubles, connected with elastic vibrations of long moving rods are avoided, there being no mechanical moving parts extending from the top of 50 the well to its bottom; the possibility of removing from the well for cleaning the operating portion only of the mechanism; a very 55 high coefficient of efficiency possible; the possibility to use the available rod pumps and their parts.

I claim as my invention:

1. In an oil well pump, the combination 60 with a reciprocating pump at the bottom of an oil well in a casing pipe adapted to pump the oil through said casing pipe, of an auxiliary reciprocating plunger in a cooperative relation with said pump, a cylinder enclosing 65 said plunger and supported inside of said cas-

ing pipe, the walls of said cylinder forming a clearance within said casing pipe, a pipe extending from said cylinder and attached thereto inside of said casing pipe to the top of said well; a liquid filling said pipe and said cylinder, a pump at the top of said well, one side of said top pump being connected with said bottom pump through said inside pipe, the other side of said top pump being connected with said casing pipe, a check valve at the top of said casing pipe, and a pipe extending from said plunger and slidably fitted in said inside pipe, adapted to conduct said liquid to the other side of said plunger.

2. In an oil well pump, the combination 80 with a reciprocating pump fitted at the bottom of a casing pipe in an oil well, of an auxiliary cylinder supported inside of said casing pipe in a coordination with said pump, a plunger in said cylinder, a rod connecting said plunger with said pump, a pipe extending from said cylinder to the top of said well, a tube extending from said plunger and slidably fitted in said cylinder pipe and adapted to conduct an operating liquid under said plunger inside of said cylinder, said cylinder pipe being connected with one side of an auxiliary pump at the top of said well, said pipe being fastened to said cylinder, the other side of said auxiliary pump being connected with said casing pipe, said auxiliary pump being adapted to alternately move said liquid in 85 said pipes thereby operating said plunger and said bottom pump.

Signed at Berlin, in the county of Brandenburg and State of Prussia, this 10th day of June, A. D. 1929.
